UNITED STATES PATENT OFFICE

146,706

DESIGN FOR A BELT BUCKLE

Renee J. Druban, Starke, Fla.

Application February 2, 1946, Serial No. 126,185

Term of patent 3½ years

(Cl. D17—1)

To all whom it may concern:

Be it known that I, Renee J. Druban, a citizen of the United States, residing in the city of Starke, county of Bradford, and State of Florida, have invented a new, original, and ornamental Design for a Belt Buckle, of which the following is a specification, reference being had to the accompanying drawing, forming part thereof.

In the drawing:

I claim:

The ornamental design for a belt buckle, as shown.

RENEE J. DRUBAN.
